FLOTATION APPARATUS

John C. MacIntosh, Douglas, Ariz., assignor to
 Phelps Dodge Corporation, New York, N. Y., a
 corporation of New York

Application December 31, 1938, Serial No. 248,824

9 Claims. (Cl. 209—168)

This invention relates to the concentrating of mineral values from ores or other substances by the so-called flotation process, wherein a pulp containing said ores or other substances, together with flotation re-agents, is subjected to aeration and agitation to produce a value-containing froth, thereby separating said values from the barren or rocky materials, known as gangue. An object of the invention is the provision of a novel flotation apparatus whereby improved separation of the mineral values from gangue is attained, and high grade concentrates are produced with marked efficiency. Another object is to provide an apparatus whereby the roughing and cleaning of the concentrate are accomplished in one unit, as distinguished from prior practice wherein only rough concentrates are produced in one unit and are then transferred to a separate apparatus for cleaning. In attaining these objects the invention provides a new and improved control over the introduction of air into the pulp as a result of which the air is distributed throughout the pulp with particular thoroughness and effectiveness; and a novel arrangement of baffles contributing to the production of clean tailings and high grade concentrates. The apparatus provided by the invention is furthermore simple in construction, requires little power for its operation, and is inexpensive in upkeep. Further features and advantages of the invention will be hereinafter described and claimed.

In the accompanying drawings:

Fig. 1 is a view in side elevation of an apparatus constructed in accordance with the invention.

Fig. 2 is a view partly in plan and partly in horizontal section, taken on line 2—2 of Fig. 1.

Fig. 3 is a vertical sectional detail view, on an enlarged scale, taken on line 3—3 of Fig. 2.

Fig. 4 is a vertical sectional view, on an enlarged scale, taken on line 4—4 of Fig. 2.

Fig. 5 is a vertical sectional view, on an enlarged scale, taken on line 5—5 of Fig. 1.

Fig. 6 is a detail view, partly in plan and partly in horizontal section, showing the agitator and taken on line 6—6 of Figure 5.

Fig. 7 is a bottom plan view of the agitator.

Fig. 8 is an enlarged sectional detail view of the agitator, taken on line 8—8 of Fig. 6.

Fig. 9 is a view, partly in vertical section and partly in elevation illustrating an alternative means for introducing air to the shaft of the rotor or agitator.

Referring to the drawings, there is shown an enclosing cell or chamber comprising a bottom 1,

end walls 2, 3 and side walls 4, 5. The pulp is introduced into the cell, from a suitable conduit 6, through an opening 7 (Fig. 3) in the wall 2. The tailing discharges through an opening 8 in the end wall 3 into a vertical passageway 9, thence over an adjustable weir 10 of known type, into a passage 11, and then out through discharge conduit 12. By adjustment of the weir 10 in the usual way the pulp level may be regulated as desired.

Extending across the cell between end walls 2 and 3, are a plurality of baffle plates which divide the cell into compartments. Two of these plates, designated 13 and 14 respectively, converge downwardly as shown in Figure 5. Above said plates 13, 14 are upwardly converging baffles 15, 16, respectively, each of which may, as shown, comprise a plurality of plates, 15', 15'', and 16', 16'' respectively. One or more of the various baffle plates may be perforated, as indicated at 17.

The baffles may be supported in the cell in any suitable manner. For example, the ends of the plate 13, may engage in grooves 18 in the respective end walls 2, 3, while similarly the ends of plate 14 may engage in grooves 19 in said walls. Said grooves extend to the tops of said walls, to enable said plates to be conveniently inserted. The baffle plates 15 likewise may engage at their ends in grooves 20, and the plates of baffle 16 in grooves 21.

A hollow shaft 22 is journaled in suitable bearings, such as 23, 24, on cross bars 25, 26, which in turn are supported by standards 27, 28 at opposite ends of the cell. Said shaft is adapted to be rotated from a suitable power source in any convenient manner, as by pulley 29, shaft 30, and bevel gears 31, 32. The upper end of shaft 22 extends into stuffing box 33, and receives air under pressure from pipe 34. A valve 35 in said pipe may be operated to regulate the supply of air to said shaft.

At its lower end the hollow shaft 22 carries a rotor, or agitator 36 comprising a hollow cylindrical body 37 having a bottom 38 of porous material such as perforated rubber, canvas, woven wire cloth, or the like. Wings 39, extending radially from the periphery of the rotor body 37, may be provided, if desired, to assist in the agitating of the pulp. Scraper blades 40 are shown secured to the rotor below the porous element 38.

In operation, the pulp is fed into the cell through the channel 6 and opening 7, the pulp level being determined by the height of the weir 10 over which the tailings pass into the discharge channel 12. The rotor or agitator 36 is

continuously rotated, and the air under pressure supplied to said rotor by the shaft 22 passes through the bottom of said rotor and thence outwardly and upwardly through the pulp. It will be noted that the air does not pass through the side walls of the rotor and that instead it must escape through the porous medium 38. The location of said porous medium at the bottom of the rotor provides for the escape of the air against a constant static head of the pulp, and hence for its even distribution through the pulp, as distinguished from the passage of the air against variable heads in prior constructions wherein the air passes through the vertical faces of the rotor with consequent uneven escape of air into the pulp. At the same time the porous medium 38 breaks the air up into fine streams, augmenting its effective distribution. The centrifugal force incident to the rotation of the rotor furthermore imparts an outward throw to the air emerging through said porous medium, and this is accentuated by the action of the rotating scraper blades 40 against said air.

As a result of the foregoing, the air is broken up into minute streams which are so impelled as to be distributed thoroughly through the pulp. This air distribution and agitation moreover, effectively retard the settling of the metal particles or mineral values to the bottom of the cell and afford said values an increased opportunity to come into contact with the flotation reagents in the pulp.

It will be further noted that the converging baffle plates 13, 14 provide a crowding zone adjacent the rotor 36, bringing the pulp into particularly intimate contact with the air, and enhancing the effect of the latter. Above said crowding zone, and in the region of the upper portions of said plates and the lower portions of baffles 15, 16, is an expansion zone, wherein the bubbles produced by the air are afforded an opportunity to drop the gangue which is carried up therewith. Above said expansion zone, and between the converging baffles 15, 16 is a coalescing zone of froth. At the top of said baffles 15, 16, the froth drains over said baffles and passes from the interior chamber 41 into the outer chambers 42, 43, between said baffles and the respective walls 4, 5.

It will be noted that the baffle plates 13, 14 terminate at their lower ends above the bottom 1 of the cell. While the greater part of the air from the rotor 36 passes upwardly between said plates, a smaller portion (about ten percent, for example) passes beneath said plates and thence rises in the compartments 42 and 43. The froth produced in the inner compartment 41, and thence flowing over the baffles into the pulp in the outer compartments 42, 43, is subjected to a cleaning action by the air and reagents in the pulp in said outer compartments, whereby the mineral values are afforded further opportunity to separate from such gangue as may be carried in said froth. Thus, while a froth of high mineral value concentration is produced in the inner compartment its concentration is further increased by the cleaning action in the outer compartments aforesaid. From said outer compartments the froth flows into launders 44, 45 of customary type whereby it is removed.

In prior arrangements of which I am aware, the rougher concentrate is collected and transferred to a separate apparatus wherein it is subjected to a cleaning action. A very substantially greater amount of air and agitation is re-

quired to produce the rougher concentrate, since a small amount of mineral values is distributed in a large quantity of pulp, and pronounced aeration and agitation are required to enable the reagents to come into contact with the mineral particles. After the mineral values are collected into a rougher concentrate, much less air and agitation are needed to separate the small amount of gangue from the large amount of mineral.

In prior flotation work, wherein the rougher concentrate is placed in a separate machine for cleaning, clear water is generally added in the cleaning cell, owing to the greatly increased density of the concentrated material, but this addition of water causes washing of the reagents away from some of the mineral values, causing them to settle to the bottom and be carried away with the tailing. In my apparatus, however, the rougher concentrate from the inner compartment drops into a pulp of proper density, which pulp also contains reagents, thus affording the mineral values an effective opportunity to separate from the gangue. Very high concentrates and remarkably clean tailings result.

It will thus be seen that my invention not only produces a particularly effective treatment of the pulp in the inner compartment 41 to produce a froth of high mineral value concentration, but also that it provides for the cleaning of said froth in the same cell to further increase said concentration. The construction cost of my apparatus, moreover, is low, since there are no complicated parts.

The power requirements are small, inasmuch as a low speed of operation of the rotor, as compared with all-mechanical flotation machines, is sufficient; and furthermore the rotor is buoyed up by the air therein. The air also prevents the coarse material from banking around the agitator and eliminates drag. In addition, the entire mechanism may be constructed from light material, thus further reducing power consumption.

The apparatus above described is capable of handling heavy tonnages. An embodiment of such apparatus in actual operation has been treating some 200 tons of material in 24 hours, with a rotor speed of about 150 revolutions per minute. Coarse material does not interfere with its operation. As the result of the thoroughness of the aeration and agitation, moreover, a desirable uniformity of pulp density is maintained throughout the pulp column. No sand bleeders are necessary. Nor are mechanical froth removers necessary, since the froth is continually discharged into the froth launders by the effect of proper agitation.

The amount of froth produced is governed by the amount of air introduced through the porous medium 38. By varying the space between the baffle plates 13, 14 and the bottom of the cell, the amount of air into the inner and outer compartments may be regulated to vary the roughing and cleaning effects as desired.

While none of the baffles 13-16 need be apertured, the provision of openings in some or all of the baffles, as indicated at 17, enables some of the air in the inner compartment to pass through said openings into the outer compartments, and thus to supplement the cleaning action of the air which passes into said outer compartments below the lower ends of the baffle plates 13 and 14.

It will be readily understood that if desired, a plurality of the cells hereinbefore described may be connected in series, in which case the tailings flowing over the weir 10 are directed to the feed

intake of the adjacent cell, instead of to waste, and are passed into the inner compartment of said adjacent cell. The tailings from the outer compartment of the latter may then pass over the weir of said adjacent cell to waste, or to a third cell, and so on. Particularly heavy tonnages may be expeditiously handled in this manner. The cells of the series may be either on the same plane or on successively lower levels, in which case the flow of material through the series of cells is aided by gravity.

In Figure 9 I have shown an alternative means for introducing air into the rotor shaft 22. In this arrangement, bearings 23', 24' for said shaft are formed integrally, as by casting, with an intermediate hollow member 50, having an enlarged interior chamber 51. Air is led to said chamber 51 by pipe 52 which fits into an opening 53 in a wall of said member 50. The shaft 22 passes upwardly through the casting comprising said bearings 23', 24' and member 50, and is closed at its upper end in any suitable way, as by a plug 54. Near its upper end said shaft may have secured thereto a rope sheave 55 through which shaft may be driven. The bearings 23', 24' may be bolted to the respective cross bars 25, 26 in the same way as are the previously described bearings 23, 24. The shaft 22 is provided with openings 56 for receiving the air introduced into chamber 51. A thrust bearing may be provided for said shaft by a collar 57 which is secured to said shaft and rests upon a ball bearing assembly 58. Between said assembly 58 and the bearing 23' a packing gland 59 is interposed, said gland being held down by the weight of the shaft 22 and the rotor or impeller carried thereby. A packing gland 60 suitably held in place by plate 61 and bolts 62, is provided at the lower end of the bearing 24'. It will be seen that this arrangement enables air to be effectively introduced into the rotating shaft 22 without requiring a stuffing box.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

I claim:

1. Flotation apparatus comprising a cell adapted to contain a body of pulp, a rotor mounted for rotation in said cell about a substantially vertical axis, the bottom of said rotor comprising porous material, and means for passing a gas into said rotor for emergence through said porous material, said rotor having blades projecting therefrom below said porous material for imparting an outward throw to gas emerging through said material and for impelling pulp positively outwardly through the zone of gas injection.

2. Flotation apparatus comprising a cell adapted to contain a body of pulp, a rotor mounted for rotation in said cell about a substantially vertical axis, the bottom of said rotor comprising porous material, and means for passing a gas into said rotor for emergence through said porous material, said rotor having blades projecting from the periphery thereof and having other blades projecting therefrom below said porous material for imparting an outward throw to gas emerging through said material and for impelling pulp positively outwardly through the zone of gas injection.

3. Flotation apparatus comprising a cell adapted to contain a body of pulp, a rotor mounted in said cell for rotation about a substantially vertical axis, a porous medium arranged at the bottom of said rotor, means for passing a gas into said rotor for emergence through said porous medium, blades on said rotor below said porous medium for imparting an outward throw to gas emerging through said medium and for impelling pulp positively outwardly through the zone of gas injection, and baffles extending in said cell to points adjacent said blades and dividing said cell into compartments through which the pulp may circulate, said baffles diverging upwardly from points adjacent said blades to augment upward movement and circulation of the pulp.

4. Flotation apparatus comprising a cell having walls projecting upwardly from the bottom thereof and adapted to surround a body of pulp, 20 baffles within the space defined by said walls and diverging downwardly from points below the top of said cell, baffles within the space defined by said walls and converging downwardly from the first-mentioned baffles, the second-mentioned baffles terminating above the bottom of said cell, and means adjacent the lower ends of the second-mentioned baffles for supplying gas to the pulp in said cell, the convergence of said second-mentioned baffles providing a crowding zone in the lower portion of the space between said second-mentioned baffles for bringing the pulp into close association with the gas from said supplying means, and also providing a froth expansion zone above said crowding zone, the 25 divergence of the first-mentioned baffles providing a continuation of said froth expansion zone in the lower portion of the space between said first-mentioned baffles.

5. Flotation apparatus comprising a cell having walls projecting upwardly from the bottom thereof and adapted to surround a body of pulp, baffles within the space defined by said walls and diverging downwardly from points below the top of said cell, baffles within the space defined by 30 said walls and converging downwardly from the first-mentioned baffles, and means adjacent the lower ends of the second-mentioned baffles for supplying gas to the pulp in said cell, the second-mentioned baffles terminating above the bottom 35 of said cell, the convergence of said second-mentioned baffles providing a crowding zone in the lower portion of the space between said second-mentioned baffles for bringing the pulp into close association with the gas from said supplying means and also providing a froth expansion zone above said crowding zone, and the divergence of the first-mentioned baffles providing a continuation of said froth expansion zone in the lower portion of the space between said first-mentioned baffles and a froth coalescing zone above said expansion zone.

6. Flotation apparatus comprising a cell having walls projecting upwardly from the bottom thereof and adapted to surround a body of pulp, 45 means in said cell for supplying gas to said pulp, baffle means within the space defined by said walls, said baffle means dividing said cell into inner and outer compartments, said baffle means comprising baffles diverging downwardly from points below the top of said cell and baffles converging downwardly from the first-mentioned baffles and terminating above the bottom of said cell, the convergence of the second-mentioned baffles providing a crowding zone in the lower 50 portion of said inner compartment to bring the

pulp into close association with the gas from said supplying means and a froth expansion zone above said crowding zone, the divergence of the first-mentioned baffles providing a continuation of said froth expansion zone in the lower portion of the space between the first-mentioned baffles, said outer compartment having a froth receiving launder below the top of said first-mentioned baffles, the space between the top of said first-mentioned baffles and said launder providing for substantially unrestricted flow of froth from the top of said baffle means to said launder.

7. Flotation apparatus comprising a cell adapted to contain a body of pulp, a rotor mounted in said cell for rotation about a substantially vertical axis, a porous medium arranged at the bottom of said rotor, means for passing a gas into said rotor for emergence through said porous medium, blades on said rotor below said porous medium for imparting an outward throw to gas emerging through said medium and for impelling pulp positively outwardly through the zone of gas injection, and baffles extending in said cell to points adjacent said blades and dividing said cell into compartments through which the pulp may circulate, said baffles diverging upwardly from points adjacent said blades to augment upward movement and circulation of the pulp, and other baffles converging upwardly from the first mentioned baffles and providing a froth coalescing zone therebetween.

8. Flotation apparatus comprising a cell adapted to contain a body of pulp, a rotor mounted in said cell for rotation about a substantially vertical axis, a porous medium arranged at the bottom of said rotor, means for passing a gas

into said rotor for emergence through said porous medium, blades on said rotor below said porous medium for imparting an outward throw to gas emerging through said medium and for impelling pulp positively outwardly through the zone of gas injection, and baffles extending in said cell to points adjacent said blades and dividing said cell into compartments through which the pulp may circulate, said baffles diverging upwardly from points adjacent said blades to augment upward movement and circulation of the pulp, other baffles converging upwardly from the first mentioned baffles and providing a froth coalescing zone therebetween, and a froth receiving launder means below the tops of said other baffles and spaced laterally therefrom, the space between the tops of said other baffles and said launder means providing for substantially unrestricted flow of froth from said baffle tops to said launder means.

9. Flotation apparatus comprising a cell adapted to contain a body of pulp, baffles diverging downwardly from near the top of said cell, baffles converging downwardly from the first mentioned baffles, the second mentioned baffles terminating above the bottom of said cell, rotor means in the zone between said second mentioned baffles, said rotor means having a porous medium at the bottom thereof, means for supplying gas to said rotor for emergence through said porous medium, and blades on said rotor below said porous medium for imparting an outward throw to gas emerging through said medium and for impelling pulp outwardly through the zone of gas injection.
